UNITED STATES PATENT OFFICE.

MARK L. SUMMERS, OF HAMMONTON, CALIFORNIA, ASSIGNOR TO TAYLOR-WHARTON IRON AND STEEL COMPANY, OF HIGH BRIDGE, NEW JERSEY, A CORPORATION OF NEW JERSEY.

PIN STOP FOR DREDGE BUCKETS.

1,423,367.

Specification of Letters Patent. Patented July 18, 1922.

Application filed August 6, 1921. Serial No. 490,241.

To all whom it may concern:

Be it known that I, MARK L. SUMMERS, a citizen of the United States, residing at Hammonton, in the county of Yuba and State of California, have invented certain new and useful Improvements in Pin Stops for Dredge Buckets, of which the following is a specification.

This invention relates to dredges, and 10 more particularly to the means for securing the buckets in jointed or pivotal relation.

The general practice is to employ a pivot pin to connect the front eyes of one bucket to the rear eye of the next adjacent bucket, 15 the pin carrying a lug which is riveted in the lug-seat of the bucket. This practice is expensive and otherwise objectionable because of the time lost in drilling holes in the bucket and pin-lug to accommodate the 20 rivet, and in heating and driving the rivet, and sometimes in cutting out the rivet when it becomes necessary to remove the pin.

My invention aims to overcome this objectionable practice, and, stated in general 25 terms, it embodies means formed integral with the bucket which prevents the pin from moving endwise and holds the lug securely in the seat.

One embodiment of the invention is shown 30 in the annexed drawing, wherein—

Figure 1 is a sectional-elevational view of a dredge bucket constructed in accordance with my invention; and

Fig. 2 is a plan view thereof.

According to my invention, I cast the pin-holding element integral with the bucket and preferably in the form of a semi-circular or 35 segmental lug or overhang 5, of which one is provided on the outside of each front eye.

The lug 5 constitutes a stop to prevent 40 endwise displacement of the pin 7 and dispenses with the use of rivets. The lug 8 of

the pin is accommodated in the slot or channel 9 and is retained therein by the segmental lug or overhang 5. In order to 45 make possible the assemblage of the pins, the eyes are somewhat elongated as indicated. Since the overhang 5 also operates to confine the lug 8 to its seat 9, it is evident that there cannot be sufficient lateral play of 50 the pivot pin to enable it to escape past the overhang. Moreover, there is always tension on the pins due to the weight of the buckets notwithstanding that the bucket line runs slack.

Having described my invention, I claim:—

1. A dredge bucket having a pin opening and a lug-seat, a pin for said opening and having a lug adapted to said lug-seat, and means cast integral with the bucket to prevent endwise displacement of the pin and effective to confine the lug to its seat. 55

2. A dredge bucket having a pin opening and a lug-seat, a pin for said opening and having a lug adapted to said lug-seat, and 60 an element overhanging the pin opening to prevent endwise displacement of the pin and effective to confine the lug to its seat. 65

3. A dredge bucket whereof each front eye is formed with an overhang in line with 70 the lug-seat, said overhang operating to prevent endwise displacement of the pivot pin and confining the lug to its seat.

4. A dredge bucket whereof each front eye is formed with a segmental stop in line 75 with the lug-seat, said stop operating to prevent endwise displacement of the pivot pin and confining the lug to its seat and ensuring uniform wear on the pin and lug-seat. 80

In testimony whereof I affix my signature.

MARK L. SUMMERS.
